(57) **CLAIM**

The ornamental design for a studded airway stent, as shown and described.

DESCRIPTION

FIG. 1 is a perspective view of an exemplary studded airway stent;

FIG. 2 is a front view of an exemplary studded airway stent; FIG. 3 is a rear view of an exemplary studded airway stent; FIG. 4 is a right side view of an exemplary studded airway stent;

FIG. 5 is a left side view of an exemplary studded airway stent;

FIG. 6 is a top view of an exemplary studded airway stent; and,

FIG. 7 is a bottom view of an exemplary studded airway stent.
